ATTORNEY

UNITED STATES PATENT OFFICE

RAY P. PERRY, OF UPPER MONTCLAIR, NEW JERSEY, ASSIGNOR TO THE BARRETT COMPANY, A CORPORATION OF NEW JERSEY

SHINGLE

Application filed March 21, 1922. Serial No. 545,414.

This invention relates to a shingle. It relates more particularly to a shingle of the type which comprises a base of felted fibrous material or the equivalent that is saturated with waterproofing material, such as asphalt for example, and coated with a coating of plastic material such as asphalt for example, to which is applied over the whole or a part thereof a layer or layers of wear-resisting material such as crushed mineral matter like slate, stone, etc.

By this invention the user is enabled to install a roof of attractive appearance and at the same time procure a variety of effects or ornamental designs without an inordinate expense. The shingle produced by this invention has a thick butt, thus adding to the attractiveness of the roof and avoiding the monotonous appearance, and at the same time the shingle is rendered more stiff, thereby decreasing the danger of the same curling up or being turned up by the wind. The invention will be understood from the description in connection with the accompanying drawings in which

Fig. 1 is a plan view of a sheet of roofing material from which the shingle is made.

Fig. 2 is an end view of the same shown in the folded position.

Fig. 3 is a plan view of the shingle.

Fig. 4 is an end view of a modification.

Fig. 5 is a plan view showing a modification of the sheet.

In the drawings reference character 1 indicates a sheet of felt or similar material which may be saturated with waterproofing material in the ordinary way. A layer of plastic material 2, such as asphalt for example, may be applied longitudinally of this sheet, this layer preferably covering only a portion of the sheet 1 and being applied intermediate the edges of said sheet. To the face of the layer of plastic material 2 is applied a layer 3 preferably of granular wear-resisting material, such as crushed stone, slate, etc.

In order to enhance the ornamental effect, as will be evident from the description, the layer 3 of crushed mineral may be composed of two portions 3' and 3'' of different or contrasting colors, which will preferably be in

contact with each other along the line 4. After the layer 3 has been applied, the sheet 1 may be folded longitudinally along a line intermediate the edges of the layer 3, as indicated in Fig. 2. When the layer 3 is composed of strips 3' and 3'' of different colors, the sheet 1 will preferably be folded along the junction line 4 of these strips, so that the mineral wear-resisting material 3' of one color will be on one side of the shingle and the wear-resisting material 3'' of the contrasting color will be on the other side of the shingle as indicated in Fig. 2. The strips 3' and 3'' of wear-resisting material may be slightly spaced from each other instead of contacting with each other along the line 4, and when so spaced, the sheet 1 will be folded so that this space will be along the folded line. The sheet 1 may be cut transversely either before or after it has been folded, thus producing individual shingles of the desired width as indicated in Fig. 3.

Instead of folding the sheet 1 as indicated in Fig. 2, the same may be folded as indicated in Fig. 4, so that the edges do not come together at one end of the shingle but come together as indicated at 5, Fig. 4. It will be obvious that the mineral surfacing material 3 may be so applied to the sheet 1 or the sheet 1 may be so folded that there is a larger area of mineral surfacing on one side of the single than on the other if desired. By having the contrasting colors of material on the two respective sides of the shingle, the dealers may keep in stock substantially one-half the material and still be able to supply the needs of customers who desire either one of the two colors, and at the same time the user can have a variety of effects produced by exercising care in the installation of the shingles with appropriate reversals of colors.

In the modification shown in Fig. 5 the sheet 10 of saturated felt or the like may have applied thereto a thick coating of plastic material 11 and thinner coatings of plastic material 12 on both sides of the coating 11, and coarse granular material 13 may be applied to the coating 11 while fine granular material 14 may be applied to the coating 12. In case the coating 13 is made of two colors, 100

as above described in connection with coating 3, the coatings 14 adjacent thereto may be made of the same or different colors. Instead of applying a thick coating 11 of plastic material and then coatings 12, as just described, 5 one entire side of the sheet 1 may be covered with plastic material and fine mineral material applied thereto entirely of one color or different portions of different colors if desired, after which another coating of plastic material 11 may be applied longitudinally of 10 the sheet on top of the coating of fine granular material, and then the coarse granular material applied thereto in the usual way.

15 Regardless of the width of the thickening portion of plastic material and wear-resisting material, and the manner of folding the sheet, in the various modifications shown by me, it will be obvious that a thickened wear-resisting surface is produced which is equal 20 to or greater in width than that desired to be exposed to the elements as the shingle is laid upon the roof in over-lapping courses with other shingles.

25 While the sheet 1 has been described as of the proper width for the length of a single shingle when folded, it is to be understood that the sheet 1 may be sufficiently wide so that a plurality of layers 3 may be applied 30 longitudinally thereof, the sheet then slit and the slits folded and cut to produce individual shingles. Instead of cutting the sheet 1 transversely at intervals sufficiently to produce single shingles, the same may be cut 35 transversely at intervals sufficiently far apart to produce a plurality of shingles, the same having notches to simulate tabs or shingles in the well known way. In the specification and claims the word "shingle" is to be understood as meaning either a single shingle 40 or a plurality of the same.

In order to insure that the plies of the sheet 1 will stick together after the same is folded, cementitious material such as asphalt for example may be applied and the plies of the sheet 1 pressed firmly together.

I claim:

1. As a new article of manufacture, a shingle having at one end, only two plies of saturated felt and two layers of mineral wear-resisting material and having at its other end, 50 only two plies of saturated felt.

2. As an article of manufacture, a shingle comprising a flexible waterproofed base folded upon itself along the median line thereof so as to form a two-ply base throughout its entire length and width and having portions of its sides near the folded portion covered with mineral wear-resisting material to different 55 extents.

60 3. A shingle comprising a saturated felt base folded upon itself along the median line thereof so as to form a two-ply base throughout its entire length and width, the segments so produced being cemented together in direct

contact with each other throughout substantially their entire area, said base having a portion of its surface along said median line coated with mineral wear-resisting material.

4. A shingle comprising a saturated felt base folded upon itself along the median line thereof so as to form a two-ply base throughout its entire length and width, the segments so produced being cemented together in direct contact with each other throughout substantially 70 their entire area, said base having a portion of its surface on each side of said median line coated with a different sort of mineral wear-resisting material than upon the other side.

5. A shingle comprising a felted foundation impregnated with a waterproofing material and folded upon itself so as to form a two-ply base throughout its entire length and width, a coating of asphalt upon the face and back of said felted foundation, said coating having crushed mineral partially embedded therein, a second coating of asphalt upon the exposed face, the butt edge and a portion of the underside of said shingle and crushed wear-resisting material partially embedded 85 in said second coating of asphalt.

In testimony whereof I affix my signature.
RAY P. PERRY.
